(57) **CLAIM**

The ornamental design for a cylindrical cage for a filter, as shown and described.

DESCRIPTION

FIG. 1 is a perspective view of a cylindrical cage for a filter showing my new design; and,

FIG. 2 is a side elevational view.

The broken line showing is included for the purpose of illustrating and forms no part of the claimed design.

1 Claim, 2 Drawing Sheets

FIG. 1

FIG. 2
